[57] **CLAIM**

The ornamental design for a dog transportation box, as shown and described.

DESCRIPTION

FIG. 1 is a perspective view taken from the top, front and left side of a dog transportation box showing my new design;

FIG. 2 is a front elevational view thereof, the rear being plain and unornamented;

FIG. 3 is a left side elevational view thereof, the right side being a mirror image; and,

FIG. 4 is a top plan view thereof, the bottom is plain and unornamented.
